UNITED STATES PATENT OFFICE

2,611,107

ELECTRIC LIGHTNING ARRESTER

Gösta Rydbeck, Västerås, Sweden, assignor to
 Allmanna Svenska Elektriska Aktiebolaget,
 Västerås, Sweden, a corporation of Sweden

Application June 21, 1951, Serial No. 232,699
 In Sweden September 24, 1941

Section 1, Public Law 690, August 8, 1946
 Patent expires September 24, 1961

8 Claims. (CL 315—36)

1

For a long time it has been clear that a reduction of the length of high tension lightning arresters has been most desirable. A possible solution has been to build together a number of closed lightning arrester units with insulating porcelains to a frame work in which the lightning current path is zig-zag formed. Such an arrangement requires, however, much space and the capacitance voltage distribution is combined with difficult problems, the solution of which requires large shielding devices.

Another possibility is to build up the arrester in a porcelain cylinder with a large diameter but with a reduced height, in which the arrester units are arranged in a plurality of columns electrically series-connected. Also in this case it is very difficult to attain a good voltage distribution.

The present invention concerns a design of lightning arresters of the latter kind but using insulating separators which also serve as condensers aiding to perform the voltage distribution over the arrester. The arrester units are mounted in two or a plurality of columns side by side, and a plurality of insulating separators are inserted in them, so that the columns are divided into short pieces containing gap elements, valve resistor elements, or both, over which the voltage is rather limited. By the division of the columns into comparatively short pieces the advantage is gained that on the same level there will not be any severely high tension between the different columns, which would cause a flash-over between the columns or an unfavorable voltage over the whole arrester, regarded as a unit. The connections between the columns can either be attained by separate metal connections or thereby that all or some of the insulating separators are provided with conductive coatings and are made so large that they, when interposed in the columns, will reach from one column to an adjacent column.

A characteristic feature of the invention is that the insulating separators will act as condensers coupled in parallel with the main current path and thus will aid in equalizing the voltage distribution before sparkover and at extinguishing.

By increasing the number of columns, the height of the arrester can be considerably reduced, but the reduction of the height is limited on one hand with respect to the necessary creepage strength inside the arrester, and on the other hand with respect to the necessary outer flash-over distance. The highest number of columns which may be used will certainly be three to five, dependent upon the kind of construction ele-

2

ments used. The electric stress per unit of length of the valve resistor columns will be of the same order of magnitude in all modern types of arresters having resistors containing silicon-carbide, whereas the spark gap elements will require a very different space dependent on the design.

The principle of the invention will be entirely clear from the accompanying drawings, on which the Figs. 1a-5a schematically show five different embodiments of the invention, whereas Figs. 1b-5b show the corresponding equivalent wiring diagrams for these forms. Figs. 6 and 7 show in section and in a view partly sectioned an arrester according to Fig. 1.

In Fig. 1, 1 designates an insulating cylinder, for instance of porcelain, which at the lower and upper ends is closed by covers 2 of metal, which covers also serve as terminals. In the cylinder 1, two columns of valve resistor elements consisting of resistor blocks and spark gap elements are arranged side by side. On the drawing the valve resistor elements are designated by 3 and the spark gap elements by 4. The columns are divided into a plurality of portions by means of insulating separators 5. The different portions of the columns spaced by the insulating separators 5 are connected in series by means of metal connections 6, which consist of metal sheets 7 interposed between the separators 5 and the valve resistor blocks 3, which sheets are connected by flexible conductors. This embodiment of the invention is one of the simplest that can be imagined and is combined with the advantage that the insulating separators can be made from turned porcelain, which is of great importance when they are double cup-shaped from a ceramic material, the side walls then serving to prevent flashover between the columns.

The form shown in Fig. 2 differs from the preceding one chiefly therein that some of the insulating separators 7 are made so large that they can be interposed into two adjacent columns, the conductive coatings on the side of these separators thus extending from one column to the other and thus serving as connections between the columns. The conductive coatings on the other separators are interconnected by means of separate metal connections 8.

When a steep over-voltage wave reaches a diverter of the hitherto known kind, the capacitance current through the spark gaps may be so large that there will be a considerable voltage drop in the resistors. Due to this fact only a minor part of the over-voltage will fall on the

spark gaps, which means an increase of the sparkover voltage of the arrester. For such steep over-voltages the device shown in Fig. 2, however, is combined with the advantage that the valve resistor elements 3', which do not contain spark gaps, will be connected in parallel with the capacitors formed by the larger separators 7, which means that the above mentioned increase of the sparkover voltage is considerably reduced.

The form shown in Fig. 3 has three columns of valve resistor elements and spark gap elements arranged side by side according to the same principle as shown in Fig. 1. The equivalent wiring diagram, Fig. 3b, shows that by this device two capacitance dividers are attained connected in parallel with the chain of resistors and spark gaps.

In the form shown in Fig. 5, all spark gap elements 4 are assembled in one column, whereas the resistor blocks are assembled in two columns arranged side by side with this column. Also this form contains in the same manner as the form shown in Fig. 2 insulating separators 7 extending from one column to another, and smaller separators 5 which are interposed in the resistor columns. Fig. 5b shows that two capacitance divider chains are attained, which are connected in parallel with the same current path of the diverter. These chains are formed by the capacitance of the small separators 5, but further the resistor blocks 3 are connected in parallel with capacitances formed by the large separators 7.

In the form shown in Fig. 4, the spark gap elements, as in Fig. 5, are assembled in one column and the resistors in two columns beside of that column. This form is a modification of the form shown in Fig. 5 in that the small separators 5 and the metal connections 8 are removed. In this form no complete capacitance divider chain is formed, but certain groups of valve resistor elements and spark gap elements are coupled in parallel with capacitors formed by the separators 7. In spite of the fact that this form seems to be very simple, it is, however, in comparison with the form shown in Figs. 1-3, combined with the disadvantage that the large separators 7 cannot be made by turning. This is of course also the case with the device in Fig. 5.

Fig. 6 shows in detail the design of the device indicated in Fig. 1. In this figure, 11 is an insulating cylinder, suitably of porcelain, which at both ends is closed by metal covers 12, which are pressed against gaskets 13 by spring members 14 attached to flanges 15. 12' are further covers closing openings in the flanges 15. In the cylinder, there are two columns of valve resistor blocks or elements 16 and spark gap elements 17. The spark gap elements consist of metal plates 18 separated from each other by spacers, which may be made from a resistance material and thus serving as grading resistors, these spark gap elements being object of the U. S. A. Patent No. 2,324,102. 20 is a centring bolt of porcelain or some other insulating material. The columns are divided into a plurality of portions by means of separators 21 of porcelain or of some ceramic material having a high dielectric constant. These separators are provided with collars 22, which prevent flashover between the columns. The resistor blocks 16 and spark gap elements 17 are inserted in cylinders 23, preferably of porcelain. In order to ensure a good contact between the different portions of the columns, helical springs 24 are inserted. The connections between the columns are performed by means of metal plates or

washers 25 interposed between the resistor blocks and the separators, and interconnected by means of flexible conductors 26. In order to improve the contact between these metal washers 25 and the insulating material in the separators 21 for attaining the highest possible capacitance, the surface of the separators may be metallized or covered by some conductive coating.

27 is a terminal intended to be used for the connection of an operation counter. In the case that no such one is used, this terminal is connected to earth. 28 is a collar of insulating material intended to stay the columns at one or several points and thus relieve them from acceleration forces during transport. When the diverter has been assembled, the cylinder 11 is evacuated and filled with some inert gas and then closed by closing the opening 29 by soldering or welding.

Fig. 7 shows in perspective view the lower end of the diverter according to Fig. 6, the cylinder 11 being partly broken away and one of the separators 21, 22 also being opened.

I claim as my invention:

1. A lightning arrester comprising a plurality of parallel columns of elements, one of said columns containing at least spark gaps and another containing at least voltage dependent resistances, insulating members separating elements of said columns, said members having on both sides layers of conducting material, means connecting elements of the columns in a series connection which includes alternately at least one spark gap and at least one resistance at adjacent levels in said columns, said layers being connected at spaced points of said series connection, and the series connection extending from one side of one of the members of a first column to a second column and back to the other side of said member through at least one element of the second column, whereby said member and the layers thereon constitute a condenser connected in parallel with such element of the second column.

2. In a device as claimed in claim 1, a single housing of insulating material enclosing all said columns.

3. A lightning arrester comprising a plurality of parallel columns of elements, one of said columns containing at least spark gaps and another containing at least voltage dependent resistances, insulating members separating elements of said columns, said members having on both sides layers of conducting material, means connecting elements of the columns in a series connection which includes alternately at least one spark gap and at least one resistance at adjacent levels in said columns, said layers being connected at spaced points of said series connection, and the series connection extending from the top side of one of the members of a first column to the bottom side of one of the members of a second column and back to the lower side of said first member through at least one element of the second column, whereby said first member and the layers thereon constitute a condenser connected in parallel with such element of the second column.

4. In a device as claimed in claim 3, said members having cylindrical skirts thereon.

5. In a device as claimed in claim 4, the skirts of the members in one column being in partial vertical alignment with those of the members in another column.

6. A lightning arrester comprising two parallel columns of elements, one of said columns containing at least spark gaps and another contain-

ing at least voltage dependent resistances, insulating members separating elements of said columns, said members having on both sides layers of conducting material, means connecting elements of the columns in a series connection which includes alternately at least one spark gap and at least one resistance at adjacent levels in said columns, said layers being connected at spaced points of said series connection, and the series connection including a jumper connection extending from the top side of one of the members of the first column to the bottom side of one of the members of the second column located higher than the first member, said series connection then extending through at least one element of the 15 second column to the top side of the next lower member thereof, and then to the bottom side of the first member, whereby said first member and

the layers thereon constitute a condenser connected in parallel with such element of the second column.

5 7. In a device as claimed in claim 6, said members having cylindrical skirts thereon.

8. In a device as claimed in claim 7, the skirts in one column being in partial vertical alignment with the skirts of the other column.

GÖSTA RYDBECK.
